HYDRAULICALLY UNBALANCED WEAR PLATE
Philip B. Spencer, Royal Oak, and Philipp Becker, Utica,
Mich., assignors to Thompson Ramo Wooldridge Inc.,
Cleveland, Ohio, a corporation of Ohio
Filed June 19, 1963, Ser. No. 288,970
5 Claims. (Cl. 103—126)

This invention relates to improvements in high pressure positive displacement pumps and more particularly relates to such pumps having an improved wear plate structure unbalanced to be forced against the end wall of the pumping chamber by the differential in pressure between the inlet and outlet of the pump.

Heretofore pressure loaded gear pumps have maintained a close clearance between the gears and the end walls of the pumping chamber by the use of a pressure loaded wear plate and the bleeding of pressure to the wear plate to bias the wear plate toward the end walls of the pumping chamber.

With such pumping and wear plate structures, however, it has been difficult to maintain the proper unbalance of the wear plate to uniformly seal the wear plate to an associated end wall of the pump housing except by complicated structures which materially increase the cost of the pump and make the pump impractical, due to expense, for installations requiring an efficient low cost pumping structure.

The present invention has as its principal object to overcome these difficulties by providing an improved wear plate structure and maintaining the wear plate in firm contact with the associated end wall of the housing by subjecting the wear plate to the unbalanced intake and delivery pressures of the pump over predetermined areas thereof.

Another object of the present invention is to provide a simplified and improved form of pressure loaded gear pump having a novel form of wear plate structure maintained in position by the differential between intake and delivery pressure of the pump, and arranged with a view towards utmost simplicity in construction and operation.

A still further object of the invention is to provide a simple and improved form of gear pump structure having a pressure loaded wear plate, in which passageway means are provided to bias the wear plate into sealing engagement with the end wall of the housing by the difference between intake and delivery pressure and in which the wear plate may loosely fit along the peripheral wall of the pumping chamber and is maintained in sealing contact therewith by subjecting an edge portion of the wear plate to delivery pressure.

Another object of the invention is to improve upon the pressure loaded gear pumps heretofore constructed by providing a passageway means from the inlet into the pumping chamber subjecting one side of the wear plate to inlet pressure and other passageway means in communication with the outlet from the pumping chamber subjecting a portion of the area of the wear plate to delivery pressure.

Still another object of the invention is to provide a means for unbalancing the wear plate of a pressure loaded gear pump and maintaining the wear plate in sealing engagement with the associated end wall of the pumping chamber by providing passageway means in communication with the inlet to the pumping chamber and extending along the wear plate in opposite directions from the inlet end of the pumping chamber to a region close to the high pressure region of the pumping chamber, and by providing other passageway means on the opposite side of the wear plate from the first mentioned passageway means and extending in opposite directions from the outlet from

2

the pumping chamber along the wear plate to the low pressure side of the pumping chamber and unbalancing the wear plate toward the end wall of the pumping chamber to accommodate fluid at discharge pressure to firmly hold the wear plate against the end wall of the pumping chamber.

A still further object of the invention is to provide an improved form of wear plate for pressure loaded gear pumps having a groove in one side thereof in communication with the inlet to the pumping chamber and extending along the side of the wear plate abutting an end wall of the pumping chamber to a region close to the high pressure region of the chamber, and having a groove on the opposite side thereof in communication with the outlet from the pumping chamber and extending along the wear plate in opposite directions from the outlet toward the low pressure side of the pumping chamber, and having relief along the edge of the wear plate in the region of the outlet and subjecting the wear plate along its edge to fluid under pressure to provide sealing contact between the wear plate with the peripheral wall of the pumping chamber at the intake side thereof.

These and other objects of the invention will appear from time to time as the following specification proceeds and with reference to the accompanying drawings wherein:

FIGURE 1 is a sectional view taken through a gear pump showing a wear plate constructed in accordance with the principles of the present invention in abutting engagement with one wall of the pumping chamber;

FIGURE 2 is a partial fragmentary sectional view taken transversely through the pumping chamber and showing certain details of the wear plate structure;

FIGURE 3 is a partial fragmentary sectional view taken substantially along line III—III of FIGURE 2 and showing a part of the wear plate structure; and

FIGURE 4 is a partial fragmentary transverse sectional view taken through a pressure loaded gear pump constructed in accordance with the principles of the present invention and illustrating a modified form in which the invention may be embodied.

In the embodiment of the invention illustrated in the drawings, we have shown in FIGURE 1 a pump housing 10, one end of which may be closed by an end plate (not shown) in a conventional manner and having an inner end wall forming an end wall of a pumping chamber 11. The pumping chamber 11 has an opposite end wall 12 and a peripheral wall 13 in the general form of a figure 8. An inlet 15 leads through the peripheral wall 13 into the region of juncture of the peripheral circumferential wall portions thereof. The housing 10 also has an outlet 16 leading therefrom in alignment with the inlet, and on the opposite side of the pumping chamber from the inlet.

A drive gear 17 is shown in FIGURE 4, as having the usual radially extending circumferentially spaced teeth 18 having close sliding contact with the upper circumferential wall portion of the pumping chamber 11. The drive gear 17 is suitably secured to a transverse shaft 19 journalled in the housing 10 on a bearing 20 on one of its ends and suitably journalled in the end cover (not shown) at its opposite end.

The gear 17 meshes with and drives a gear 21, the teeth of which have close sliding contact with the lower circumferential wall portion of the pumping chamber. The gear 21 is suitably mounted on a shaft 22 suitably journalled in the housing 10 and end cover therefor, in a conventional manner.

As shown in FIGURES 1 and 2 a wear plate 25 is interposed between the sides of the gears 17 and 21 and the end wall 12 of the pumping chamber. It is customary to pressure load a gear pump at only one end, although

under certain conditions it may be desirable to have two wear plates, one abutting each end wall of the pumping chamber. Where two wear plates are used, the construction and operation of each wear plate is the same, so the construction of one wear plate only need herein be shown or described in detail.

The wear plate 25 may be of a laminated construction having a bearing face 26 facing and slidably engaged by the gears 17 and 21. While the wear plate 25 is shown as being of a laminated construction, a bearing surface for the gears 17 and 21 may be coated thereon by a conventional coating process, if desired.

The wear plate 25 is shown in FIGURE 1 as being in the general form of a figure 8 in plan, conforming to the peripheral wall 13 of the pumping chamber and having a relatively loose fit therein. A groove 27 in communication with the inlet 15 extends inwardly along the plate 25 at the intersection of the circumferential portions of said plate. The groove 27 is on the side of the wear plate 25 facing the wall 12 and has communication with grooves 29, 29 extending in opposite directions from the groove 27 and generally conforming to the periphery of the plate 25 in radially inwardly spaced relation with respect to the periphery thereof. The grooves 29, as shown in FIGURE 3, extend from the intake or suction side of the pump and terminate at diametral line A in the region of the high pressure side of the pump, it being of advantage to extend the grooves close to the point where the gears build up the maximum pressure of fluid for discharge through the outlet 16.

Similar grooves 30 are formed in the opposite side of the wear plate 25 from the grooves 27 and 29 and extend in opposite directions from the discharge side of the pump along the wear plate in general conformity to the periphery of the wear plate to diametral lines B at the suction side of the pumping chamber. Discharge pressure acting on the wear plate 25 along the grooves 30 will thus unbalance the wear plate in a direction of the hydraulic force FH_1 and thereby keep the wear plate from moving and uniformly contact the wear plate with the wall 12 of the pumping chamber.

The edge of the wear plate 25 along the pressure side of the pumping chamber, is shown in FIGURE 3 as being relieved as by a bevel 33 extending in opposite directions along the discharge or pressure side of the pumping chamber from the juncture of the circular wall portions of the wear plate and gradually merging into the wear plate. This relief or beveled edge forms an increased area surface along the pressure edge of the wear plate upon which the fluid at discharge pressure acts and forces the wear plate in the direction FH_2 against the peripheral wall of the pumping chamber and thereby counteracts for a relatively loose fit of the wear plate and forces the wear plate to form a contact seal with the peripheral wall of the pumping chamber at the intake side thereof.

In the modified form of the invention shown in FIGURE 4 a groove 35 is formed in an end wall 12a of the pumping chamber. The groove 35 may be of the same general form as the grooves 27 and 29, 29 and extends along the wall of the pumping chamber to a position as close to the high pressure region of the pump as possible. A groove 36 is shown as being formed in a wear plate 25a and opening toward the gears 17 and 21 and having communication with the pressure side of the pump and extending about the wear plate to the same extent the grooves 30 extend along the wear plate 12.

It may be seen from the foregoing that we have improved upon the high pressure gear pumps heretofore in use by providing a simplified form of unbalanced wear plate, in which the side of the wear plate abutting the end wall of the pumping chamber is subjected to intake pressure or suction, and the opposite side of which is subjected to the pressure of the discharge side of the pump, and that the portions of the wear plate subjected to positive and negative pressure are so unbalanced as

to assure firm contact of the wear plate with the end wall of the pumping chamber.

It may further be seen that the wear plate is so constructed that it need not be tightly fitted into engagement with the wall of the pumping chamber and may be relatively loose in the pumping chamber and forced against the wall of the pumping chamber by the delivery pressure of the fluid to form a contact seal with the peripheral wall of the pumping chamber and reduce the losses in flow that would otherwise be present with a loose fitting wear plate.

While we have herein shown and described several forms in which our invention may be embodied, it may readily be understood that various modifications and variations in the invention may be attained without departing from the spirit and scope of the novel concepts thereof.

We claim as our invention:

1. In a high pressure gear pump, a housing having a hollow interior portion forming a pumping chamber having parallel spaced end walls and an internal peripheral wall in the general form of a figure 8, a pair of shafts rotatably journaled in said housing and having meshing gears mounted thereon and disposed in said pumping chamber between said side walls and in close contact with said internal peripheral wall and having intersecting pitch circles, an inlet into said pumping chamber in axial alignment with said pitch circles at the point of intersection thereof, said gears and pumping chamber establishing a suction area in the region of said inlet, an outlet from said pumping chamber leading from the opposite side of said pumping chamber from said inlet and in axial alignment therewith, said gears and pumping chamber establishing a high pressure area in the region of said outlet, at least one wear plate in said pumping chamber free from said shafts and abutting an end wall of said pumping chamber and generally conforming to the peripheral wall of said pumping chamber, a groove extending along the side of said wear plate facing an adjacent end wall of said pumping chamber and opening toward said end wall, a passageway in said wear plate affording communication from said inlet to said groove, said groove generally conforming to the periphery of said wear plate and the internal wall of said pumping chamber, and being spaced closer to said peripheral wall than said shaft, and terminating at the high pressure area of said pumping chamber and subjecting the side of said wear plate facing said end wall to inlet pressure, a second groove in the side of said wear plate facing said gears and opening to said gears and being in alignment with said first groove and extending along said wear plate in opposite directions from said outlet and terminating at the suction area of said pump, said second groove having communication with said outlet and subjecting the side of said wear plate facing said gears to discharge pressure, whereby the imbalance of inlet and discharge pressure in said grooves on opposite sides of said wear plate biases said wear plate into firm engagement with said end wall of said pumping chamber.
2. A high pressure gear pump in accordance with claim 1 wherein the wear plate has a bearing face thereon on the side thereof adjacent said gears.
3. A high pressure gear pump in accordance with claim 1 wherein the wear plate has a relatively loose fit in said pumping chamber and has a chamfered edge on the side thereof facing said outlet to force said wear plate into sealing contact with the peripheral wall of said

pumping chamber by the force of the pressurized fluid in the high pressure region of said outlet.

4. In a high pressure gear pump,
 a housing having a hollow interior portion forming a pumping chamber having opposite end walls and an internal peripheral wall in the general form of a figure 8, 5
 a pair of meshing gears in said pumping chamber between said side walls and in close contact with said peripheral wall and having intersecting pitch circles, 10
 shafts for said gears journalled in said housing and mounting said gears for rotation within said pumping chamber,
 an inlet into said pumping chamber in axial alignment with the pitch circles of said gears and facing said gears as they come out of mesh, 15
 said gears and pumping chamber establishing a suction area in the region of said inlet,
 an outlet from said pumping chamber leading from the opposite side of said pumping chamber from said inlet and in axial alignment therewith, 20
 said gears and pumping chamber establishing a pressure area in the region of said outlet,
 at least one wear plate in said pumping chamber abutting an end wall thereof and spaced radially from said shafts and generally conforming to the peripheral wall of said pumping chamber, 25
 a groove in the side of said wear plate facing said gears and leading along said wear plate in opposite directions from said discharge outlet and spaced closer to the periphery of said wear plate than said shafts and generally conforming to the periphery of said wear plate and internal wall of said pumping chamber, 30

ber and terminating at the suction area of said pump and subjecting the face of said wear plate facing said gears to discharge pressure, and a groove in the end wall of said pumping chamber abutted by said wear plate opening towards said wear plate and in axial alignment with the groove in said wear plate and having communication with said inlet and extending along said end wall and generally conforming to the periphery of said wear plate and internal wall of said pumping chamber and terminating at the pressure region of said pumping chamber and subjecting the face of said wear plate facing said end wall to inlet pressure, whereby the imbalance of inlet and discharge pressure on 15 said wear plate biases said wear plate into sealing engagement with the adjacent end wall of said pumping chamber.

5. A high pressure gear pump in accordance with claim 4 in which the side of the wear plate facing the meshing 20 gears has a bearing face thereon for the side faces of said gears, and in which the edge of the wear plate facing the outlet is chamfered to effect the forcing of the wear plate into sealing engagement with the peripheral wall of the pump housing.
